UNITED STATES PATENT OFFICE.

WILLIAM HENDRY, OF TACOMA, WASHINGTON.

SHUTTLE-WINDER.

1,216,994.

Specification of Letters Patent. Patented Feb. 20, 1917.

Application filed May 12, 1916. Serial No. 97,097.

To all whom it may concern:

Be it known that I, WILLIAM HENDRY, a subject of the King of Great Britain, residing at Tacoma, in the county of Pierce and 5 State of Washington, have invented certain new and useful Improvements in Shuttle-Winders; and I do hereby declare the following to be a full, clear, and exact description 10 of the invention, such as will enable others skilled in the art to which it appertains to make and use the same.

This invention relates to a device for winding thread upon tatting shuttles, and the primary object of the invention is to 15 provide a shuttle winder, which is compact in structure, and which has a shuttle holder rotatably supported by a suitable supporting structure, which shuttle holder is constructed of a pair of telescoping sections, so 20 that it may be adjusted for holding any size of tatting shuttle.

A further object of this invention is to provide a support for the rotary shuttle holder, which is provided with a pocket in 25 one end of the same for receiving a shuttle.

With the foregoing and other objects in view this invention consists in such novel features of construction, combination and arrangement of parts as will be hereinafter 30 more fully described, illustrated in the accompanying drawings and claimed.

In describing the invention in detail reference will be had to the accompanying drawings wherein like characters designate 35 like and corresponding parts throughout the several views, and in which:

Figure 1 is a side elevation of the improved shuttle winder showing parts thereof in section.

40 Fig. 2 is an edge elevation of the shuttle winder.

Fig. 3 is a side elevation of the shuttle winder exhibiting the side opposite to the one illustrated in Fig. 1.

45 Fig. 4 is a sectional view through the shuttle holder and a portion of the supporting post therefor.

Fig. 5 is a section on the line 5—5 of Fig. 2, and

50 Fig. 6 is a section on the line 6—6 of Fig. 2.

Referring more particularly to the drawings, 1 designates the supporting body of the shuttle winder as an entirety, which is

provided with a pocket 2 extending inwardly from one end. The pocket is normally closed by a cap or hinged door 3, which door is in turn held in a closed position by an ordinary latch structure 4. The pocket 2 is provided for retaining a shuttle, 55 when not in use.

The body 1 has a stub shaft 5 carried thereby upon which a gear 6 is mounted. The gear 6 has a handle 7 attached thereto, through the medium of which the gear is 60 manually rotated. A pinion 8 meshes with the gear 6, and it is mounted upon a shaft 9, which shaft extends entirely through the supporting post or body 1 of the shuttle winder, and has the shuttle holding device 70 10 mounted upon its end remote from the end upon which the pinion 8 is mounted.

The shuttle holder structure comprises a body plate 11, which has a casing 12 which is formed of sheet metal mounted about one 75 end of the same, and a second casing 13 mounted about the other end of the same and telescopically mounted over the casing 12. The casings 12 and 13 have outwardly 80 extending or projecting lips 15 formed thereon, adjacent their ends and substantially equi-distant of their sides, as clearly shown in Figs. 3 and 4 of the drawings. The lips 15 form pockets, for receiving the 85 ends of a tatting shuttle. The telescoping 10 of the section or casing 13 with the casing 12 will permit of the attachment of different size tatting shuttles to the shuttle carrier 10.

A bail member 16 is pivotally supported 90 as shown at 17, by the body 1 and it has its ends inturned as shown at 18 for insertion into the central bore of a spool as indicated at 19. The spool 19 is of the ordinary type used for retaining thread or the 95 like, and the thread is unwound from the spool 19 and wound upon a shuttle carried by the shuttle carrier 10. A thread guide 20 is attached to the body 1 and is provided for properly guiding the thread from the 100 spool 19 to the shuttle. A guard 22 is provided for the pinion 8.

The thread is guided from the spool 19 by the guide 20, to a tatting shuttle which may be carried by the shuttle carrying member 10, and after the thread has been properly connected to the tatting shuttle, the gear 6 is rotated through the medium of the 105

handle 7 which will in turn rotate the shuttle carrying member 10 through the medium of the pinion 8 and the shaft 9, which will unwind the thread from the spool and wind it upon the shuttle.

In reducing the invention to practice, certain minor features of construction, combination and arrangement of parts may necessitate alterations to which the patentee is entitled provided such alterations are comprehended within the scope of what is claimed.

What is claimed is:—

1. In a tatting shuttle winder structure, 15 a body, a gear rotatably carried by said body, a shaft extending through said body, a pinion mounted upon said shaft and meshing with said gear, a shuttle carrying member carried by said shaft and including a 20 body, and a pair of telescoping casings mounted upon said body, said casings being provided with outstruck portions for forming pockets for receiving the ends of a shuttle, a spool holder pivotally connected to 25 said body, and a thread guard carried by said body for guiding the thread from a spool mounted upon said spool holder to a

shuttle carried by said shuttle carrying structure.

2. In a tatting shuttle winder structure, 30 a body, a gear rotatably carried by said body, a shaft extending through said body, a pinion mounted upon said shaft and meshing with said gear, a shuttle carrying member carried by said shaft and including a 35 body, and a pair of telescoping casings mounted upon said body, said casing being provided with outstruck portions for forming pockets for receiving the ends of a shuttle, a spool holder pivotally connected to 40 said body, and a thread guard carried by said body for guiding the thread from a spool mounted upon said spool holder to a shuttle carried by said shuttle carrying structure, said body being provided with a 45 shuttle receiving pocket extending upwardly from its lower end, and a hinged cover normally forming a closure for said pocket.

In testimony whereof I affix my signature in presence of two witnesses.

WILLIAM HENDRY.
